UNITED STATES PATENT OFFICE.

IGNAC KORMUTT, OF CHARLEROI, PENNSYLVANIA.

MELTING AND POURING FURNACE.

1,290,242.

Specification of Letters Patent.

Patented Jan. 7, 1919.

Application filed May 4, 1918. Serial No. 232,641.

To all whom it may concern:

Be it known that I, IGNAC KORMUTT, a citizen of Austria-Hungary, residing at Charleroi, in the county of Washington and 5 State of Pennsylvania, have invented new and useful Improvements in Melting and Pouring Furnaces, of which the following is a specification.

This invention relates to melting and 10 pouring furnaces especially adapted to be used for melting and pouring lead and similar metals and it consists in the novel features hereinafter described and claimed.

An object of the invention is to provide a 15 furnace of the character stated having means for gathering the poison gases which emanate from the material during the process of melting and pouring, there also being means for conveying the said poison gases 20 away from the furnace thereby preventing them from coming in contact with the operator and eliminating the dangers and damage incident thereto.

With this object in view the furnace comprises in a unitary structure a fire box having 25 an oven positioned at one end thereof the said oven being adapted to contain the material which is melted. A pouring chamber is located adjacent the fire box and a ladle 30 is pivotally mounted therein. A trough is provided for conveying the molten metal from the oven to the ladle and means are provided for moving the trough. A flue communicates with the melting chamber at 35 points above the ladle and the products of combustion are adapted to pass from the fire box through the melting chamber over the ladle and up through the flue. The furnace is provided with suitable air pipes 40 adapted to lead air into the same to facilitate combustion and thereby complete the consumption of the fuel which is used for heating purposes.

In the accompanying drawings:—

45 Figure 1 is a front view of the furnace.

Fig. 2 is a rear view of the same.

Fig. 3 is a longitudinal sectional view of the same cut on the line 3—3 of Fig. 1 with the lower door omitted.

50 Fig. 4 is a similar view cut on the line 4—4 of Fig. 1.

Fig. 5 is a transverse sectional view of the furnace cut on the line 5—5 of Fig. 7.

55 Fig. 6 is a detail sectional view cut on the line 6—6 of Fig. 7.

Fig. 7 is a horizontal sectional view cut on the line 7—7 of Fig. 4.

Fig. 8 is a detail sectional view cut on the line 8—8 of Fig. 7.

The furnace comprises a fire box 1 of conventional form having a grate 2 located therein in a usual manner. An oven 3 is mounted upon the fire box 1 at one end thereof and the said oven is provided at one end with a vertically slidable door 4 and a horizontally slidable door 5. Any suitable means may be provided for sliding these doors or they may be moved by hand if desired. A false bottom 6 is tiltably mounted by means of ears 6^a journaled on a rod 6^b 70 in the oven 3 and is provided at one end with a lug 7 adapted to normally rest within a notch 7^a in the upper edge of the door 5 when the said door is at a closed position at the end of the oven as indicated in Figs. 75 4 and 6. When the lug 7 is supported by the edge of the door 5 the false bottom 6 is held at a horizontal position as best shown in Fig. 6 of the drawing. When the door 5 is moved to an open position the false bottom 6 may be swung to an inclined position as shown by dotted lines in Fig. 6 whereby the material which is supported upon the false bottom 6 may gravitate out of the oven 3 through the opening which is normally 85 closed by the door 5. Any suitable means may be provided for swinging the false bottom 6 or the said bottom may be swung by hand if desired. It will be noted that the forward edge of the false bottom 6 terminates short of the front wall of the oven to provide a space 7^b for a purpose to be described.

A melting chamber 8 is located at the side of the fire box 1 and the side wall of the said box is provided with ports 9 which communicate with the interior of the melting chamber. A flue 10 is located at the side of the melting chamber 8 and the adjacent wall of the said chamber is provided with ports 100 11 which communicate with the passageways through the said flue.

A ladle 12 is pivotally mounted in the melting chamber 8 below the ports 9 and 10 and a handle 13 is attached to the delivery 105 end portion of the said ladle. Any suitable means may be provided for swinging the ladle or the ladle may be swung by hand if desired.

A spout 14 is slidably mounted below the 110

bottom of the oven 3 and the said oven is provided in its bottom with an opening 15 through which the molten metal may flow from the oven into the spout 14. When the 5 spout 14 is projected through the position shown in Figs. 7 and 8 of the drawing the molten metal which enters the same will flow along the spout and fall into the ladle 12. When it is not desired to discharge the 10 molten metal from the oven it is moved, by mechanism to be hereinafter described, so that its upper portion formed as a plate 14^a will be disposed beneath the opening 15 in the bottom of the oven and serve as a door 15 to prevent molten metal from passing into the spout. The ladle 12 is normally maintained at a horizontal position consequently it will retain the molten metal while the 20 products of combustion from the fire box are passing over the ladle and out through the flue. Consequently the metal which is in the ladle is maintained in a molten condition. When the ladle is tilted the metal may flow from the same. 25 The spout 14 is provided at its underside with a series of teeth 16 and a pinion 17 meshes with the said teeth 16. The pinion 17 is mounted upon a crank shaft 18 which passes through the side of the fire box. It is 30 apparent that by rotating the shaft 18 the spout 14 may be projected or retracted with relation to the oven and the fire box. Therefore when it is desired to tilt the ladle the spout 14 is withdrawn from over the upper 35 edge thereof and the said ladle may be readily tilted whereby the molten metal contained therein may be poured. The melting chamber 8 is open at its end below the ladle 12 consequently the molds or flasks may be 40 moved under the ladle through one end of the melting chamber and removed from under the same by passing them out at the opposite end of the melting chamber. An air pipe 19 is arranged to discharge blasts of air 45 in the fire box and melting chamber. The blast which enters the fire box passes in below the grate 2 as best indicated in Fig. 5 and the blast which enters the melting chamber 8 passes in above the ladle 12. These 50 volumes of air tend to promote combustion and will also serve as means for quickly removing the poison gases from the molten metal and for carrying the same up to the flue.

The metal to be melted is placed upon the 55 false bottom 6 and the said bottom is moved to a horizontal position and the doors at the end of the oven are closed. As the metal melts it will run over the lower edge of the false bottom through the previously de- 60 scribed space 7^b and along the true bottom of the oven and through the opening 15 and along the trough 14 into the ladle 12. Any material which should remain upon the false bottom and should not be melted may be re- 65 moved by swinging the false bottom to an inclined position and by using a scraper or suitable implement upon the said material.

From the foregoing description taken in conjunction with the accompanying drawings it will be seen that a melting furnace of durable structure is provided and that the same will effectually remove the noxious and poison gases from the metal during the time that it is being melted and also at the time 75 that it is being poured from the ladle into the molds or flasks and consequently the injurious effects of such poison gases to the workmen who are compelled to attend the furnace are eliminated. 80

Having thus described the invention what is claimed is:

1. A melting furnace comprising a fire box, an oven located thereon, a melting chamber located adjacent the fire box and communicating therewith, a flue located adjacent the melting chamber and communicating therewith, a ladle tiltably mounted in the melting chamber, a spout slidably mounted and adapted to convey metal from the oven to the ladle and means for sliding the spout. 85 90

2. A melting furnace comprising a fire box, an oven located thereon, a false bottom located in the oven and being tiltably mounted, doors provided upon the oven, one of the said doors adapted to serve as a support for holding the false bottom at a horizontal position, a melting chamber located adjacent the fire box and communicating therewith, a flue located adjacent the melting chamber and communicating therewith, a ladle tiltably mounted in the metal in the melting chamber and a movable spout adapted to convey molten metal from the oven to the ladle. 95 100 105

In testimony whereof I affix my signature.

IGNAC KORMUTT.
